UNITED STATES PATENT OFFICE.

FRANK R. ALFORD, OF WINSTED, CONNECTICUT, ASSIGNOR TO WM. L. GILBERT CLOCK COMPANY, OF WINSTED, CONNECTICUT, A CORPORATION OF CONNECTICUT.

FRICITION-HELD ALARM-SWITCH.

No. 903,125.

Specification of Letters Patent.

Patented Nov. 3, 1908.

Application filed March 14, 1908. Serial No. 421,032.

To all whom it may concern:

Be it known that I, FRANK R. ALFORD, a citizen of the United States, residing at Winsted, county of Litchfield, State of Connecticut, have invented certain new and useful Improvements in Friction-Held Alarm-Switches, of which the following is a full, clear, and exact description.

My invention relates to the alarm mechanism of so-called alarm clocks, and is concerned particularly with an improved switch for rendering the alarm inoperative when desired.

The object of the invention is to provide means for preventing accidental displacement of the switch from its operative path; to hold the switch in all positions of adjustment, and to limit the movement thereof to its effective path of operation.

With these objects in view, the invention consists in the construction and arrangement of parts, the preferred embodiment of which is illustrated in the accompanying drawings, in which

Figure 1 is a rear view of an alarm clock, the alarm bell being removed for clear illustration. Fig. 2 is a partial sectional view of the interior of the clock, the works being removed to clearly show the mounting of the alarm hammer. Fig. 3 is a sectional view on the line 3—3 Fig. 1. Fig. 4 is a detail of parts hereinafter to be described.

In the embodiment of my invention here selected for illustration, the alarm bell 1 is shown as mounted upon the rear of the clock and supported thereon in any desirable manner. The alarm hammer 2 is carried by an arm 3 pivoted upon a pintle 4 in convenient operative position with respect to the usual hammer actuating mechanism (not shown). The hammer arm 3, as shown in Figs. 1 and 2, projects through a suitably shaped opening 5 in the back plate 6 of the clock, and upon said back plate is mounted the switch 7, which, as here shown, is constructed in the form of an arm, preferably pivoted at 7' at the center of the back and extending radially thereof adjacent the path of the hammer arm 3.

In order to prevent the switch from being displaced from its operative path, by being accidentally pulled or bent away from the back plate 6, a finger 8 is provided which may be struck up from the material of the back and overlies the free end of the arm,

as clearly illustrated in Fig. 1. In order to hold the switch firmly in adjusted position, the finger 8 is provided with a friction rib 9 extending longitudinally thereof, which bears upon the arm and holds it firmly down against the back. For convenient manipulation of the switch arm the outer end thereof may be bent over the peripheral ridge 10 of the back plate, as shown at 11, Figs. 1 and 3. To limit the swing of the switch arm within its effective operative path, the attached portion of the holding finger 9 is positioned so as to engage the arm when moved to the limit of its inoperative position, thereby forming a stop or guard for movement of the arm. To limit the movement in the opposite direction, the arm may be formed with a curved portion 12 arranged to engage one of the studs 13 which serves to secure the parts of the clock in assembled position. When the switch is in the stopping position this curved portion thereof lies directly across the path of the hammer arm whereby the latter is the more effectively stopped by engagement therewith.

The preferred method of mounting the switch arm here illustrated consists in drawing up the inner end thereof to form a rivet 14 (Fig. 3), which may be upset within an aperture in the center of the back, thus leaving an unobstructed opening at the center through which the hand set 15 may project if desired. This feature, however, forms no part of the invention herein disclosed.

What I claim is:

1. In an alarm clock, an alarm bell, a hammer therefor, an adjustable switch adapted to render said alarm inoperative, means to secure said switch to the clock, and means integral with the case of the clock adjacent to said switch to hold the same in its operative path and to hold it in all positions of adjustment.

2. In an alarm clock, an alarm bell, a hammer therefor, a switch adapted to render said alarm inoperative and means integral with the case of the clock and over-lying said switch to hold the same in its operative path and to hold it in operative and inoperative positions.

3. In an alarm clock, in an alarm bell, a hammer therefor, and switch arm pivoted at the center of the back of said clock and adapted to render said alarm inoperative,

and means integral with said back and adjacent to the outer extremity of said switch to protect the same against displacement from its operative path.

- 5 4. In an alarm clock, an alarm bell, a hammer therefor, a switch adapted to render said alarm inoperative, means to secure said switch to the clock and a tongue having a

friction rib mounted adjacent to said switch to hold the same in all positions of adjustment. 10
